UNITED STATES PATENT OFFICE.

ARTHUR SHELDON WELDY, OF CANTON, OHIO.

PUMP.

Application filed December 21, 1927. Serial No. 241,856.

My invention relates to pumps, and particularly to pumps of that class which have a cylinder or rotor provided with two or more piston-equipped cylinders disposed in balanced relation and parallel to the axis of rotation.

It relates particularly to a unitary device of this character adapted to pump a plurality of different liquids, and in which the rate of pumping any liquid may be very minutely regulated independently of the rate at which any of the other liquids is pumped.

The objects of my invention are to provide a pump of this character which is inherently balanced and which may be operated at very high speeds without noise or vibration. Another object of my invention is to provide a pump of this character, comprising a single unit, which will be adapted to pump a plurality of different liquids or which, if desired, may be adapted to pump the same liquid at different rates to several discharge points. Another object of my invention is to provide a device of this character which is susceptible of minute regulation so that it may be set to accurately discharge a liquid at any predetermined rate from zero up to the capacity of the pump. A further object of my invention is to provide a device of this character in which the discharge rate of any of the liquids being pumped may be minutely regulated independently of the rate at which any of the other liquids are being discharged.

With these objects in view my invention includes the novel elements and combinations of elements described below and illustrated in the accompanying typical drawings in which—

Fig. 1 is a fragmentary front view, partially in section, of my pump;

Fig. 2 is a section of Fig. 1 in the plane 2—2;

Fig. 3 is an inside elevation view of the cover plate;

Fig. 4 is a section of Fig. 3 in the plane 4—4;

Fig. 5 is an elevation view of the adjustable cam plates; and

Fig. 6 is a section of the cam plates in the plane 6—6 of Fig. 5 showing how these plates are movable relative to each other.

Referring to the drawings, my pump comprises a cylindrical cup-like casing, 1, provided at the open end with the flange, 2, and

having suitable supports, 3 and 4. This casing is adapted to be closed by the cover plate, 5, which is secured to the flange by means of the bolts, 6. The cover plate is provided with a center opening, 7, which forms a bearing for the rotor shaft, 8'. The inner side of the cover plate, 5, is provided with circumferential grooves or channels, 8, 9, 10, 11, 12 and 13, the function of which will be explained later. These grooves communicate with holes, 14, 15, 16, 17, 18 and 19, which extend entirely through the cover plate and are threaded to receive pipes, as shown at 20, 21 and 22 in Fig. 3.

Preferably integral with the shaft, 8', is the rotor, 23. This rotor may be of any size and may carry any number of pairs of pumping units, each pair of which is symmetrically disposed relative to the axis of rotation. For the purpose of illustration I have shown only three pairs of pumps.

Referring to Figs. 1 and 2, symmetrically disposed holes, 24 and 25, 26 and 27, and 28 and 29, respectively, are drilled or bored in the rotor parallel with the axis of rotation and which form the cylinders of the pump. From the rear of the rotor these holes are enlarged by counterboring as shown at 30, 31, 32 and 33, to receive the pistons, 34, 35, 36 and 37, respectively. These pistons are provided with plungers, 38, 39, 40 and 41, respectively, which reciprocate in the cylinders, 24, 25, 26, 27, 28 and 29, and form the pistons or plungers proper for the pump. Each of the pistons, 34, 35, 36 and 37, is hollowed out to form an annular space about its plunger, and a helical spring, such as 42 or 43, surrounds each of the plungers, 38, 39, 40 and 41, and is compressed between the bottom of the counterbore and the piston. These springs tend to retract the plungers from their respective cylinders.

At the back of the casing behind the rotor are the cam plates, 44, 45 and 46. The center cam plate, 46, is circular and the cam plates exterior of that are annular rings. These plates are mounted upon the axis or shaft, 47, which extends centrally through all of the plates and through the exterior of the casing, 1, where it is secured in place by means of lock nuts, 48 and 49. It will be thus apparent that the cam plates, within the space limited by the rear of the casing and the rear of the rotor, may be tilted about the shaft, 47, so that the angle of inclination of the cam plates to the axis of rotation may be varied.

Threaded through the rear casing wall and

bearing against each cam plate on opposite sides of the axis, 47, are adjusting screws, 50 and 51, for the cam plate, 44; 52 and 53, for the cam plate, 45; and 54 and 55, for the cam plate, 46. These screws are also provided with lock nuts, 56, which secure them in adjusted position. It will be evident that the inclination of cam plate, 44, may be varied by moving screws, 50 and 51, in opposite directions to each other, and in the same way the inclination of each of the other cam plates may be varied. Where space is essential, the circumferential surfaces of the cam plates which are close together must be spherical, but where space is not essential and the cam plates can be separated somewhat, these surfaces may be cylindrical. This will be particularly apparent from a consideration of Fig. 6 which illustrates the cam plates set at different angles to each other and to the axis of rotation.

The bottoms of the pistons, 34, 35, 36, 37, etc., are provided with projections terminating in balls, 57, about which are spun the conical cups, 58, which bear upon the cam plates. These balls and the conical cups provide ball and socket joints adapted for universal movement as the rotor is turned.

The rotor, 23, fits closely against the inner side of the cover plate, and the channels or grooves, 8, 9, 10, 11, 12 and 13, on the inside of the cover plate, are adapted to register with the paths described by the open ends of the pumping cylinders, 24, 25, 26, 27, 28, 29 in the rotor. In other words, the cylinder, 24, for example, depending upon whether the plunger, 38, is being retracted or compressed in the cylinder, will tend either to draw liquid from the groove, 8, and discharge into the groove, 9, or draw from the groove, 9, and discharge into the groove, 8. These grooves should be as nearly 180 degrees in extent as is possible.

The operation of my device is as follows: The rotor may be turned in either direction. If it turns in the direction of the arrow shown in Fig. 1 and the cam plates are in the position shown in Fig. 2, it will be apparent that plunger, 41, for example, as the rotor turns 180 degrees, will be retracted in cylinder, 25, until it occupies the position of the plunger, 38. During this retraction, cylinder, 25, registers with groove, 9, and any liquid which is in that groove will flow or be drawn into cylinder, 25. As the cylinder, 25, passes over the top dead center its opening comes into registration with groove, 8, and any liquid in cylinder, 25, will be forced outwardly into groove, 8, by plunger, 41, until the bottom dead center is reached. Here, groove, 8, ends, and cylinder, 25, immediately passes over into registration with groove, 9, to repeat the cycle. It will be apparent that each of the cylinders will pump and discharge into the respective grooves in the same manner. This being so,

liquids which are introduced through the openings, 15, 17 and 19 respectively, will flow into grooves, 9, 11 and 7 respectively, from which they will be picked up by the pumps and discharged into grooves, 8, 10 and 12 respectively, and thus out through the discharge openings, 14, 16 and 18, in the cover plate. The liquids may be introduced through the openings, 15, 17 and 19, by means of suitable pipes threaded therein, and discharged through pipes threaded into the openings, 14, 16 and 18.

By varying the angle of inclination of any cam plate to the axis of rotation, it will be apparent that the stroke of each pair of pistons may be varied from zero up to the maximum. As the rotor revolves, the conical pieces run on the cam plates and the plungers are positively forced into the cylinders on the compression stroke and retracted from the cylinders by means of the helical springs on the suction strokes. The compression of these springs upon the bottom of the counterbores will be sufficient to hold the rotor tightly against the inner side of the front cover plate so that leakage will be avoided. To prevent compression in the counterbores I provide the vents, 59.

From the foregoing it will be apparent that I have provided a unitary pump which is adapted to draw and distribute a plurality of different liquids at different rates. For example, where it is desired to feed oil, gasoline and water to an oil burner, these three liquids may be discharged at any rates into a common mixing device and the discharge of each liquid may be varied so that the proportion of the resulting mixture will be exactly as desired.

While I have described my invention in its preferred embodiment it is to be understood that the words which I have used are words of description rather than of limitation and that changes within the purview of the appended claims may be made without departing from the true scope and spirit of my invention in its broadest aspects.

What I claim is—

1. In a pump of the character described, the combination with a rotor having a plurality of pairs of reciprocating pumps arranged in balanced relation therein with their axis disposed parallel to the axis of the rotor but at different distances therefrom, of means for independently varying the stroke of a pair of pumps.

2. In a pump of the character described, the combination with a rotor having a plurality of pairs of reciprocating pumps arranged in balanced relation therein with their axis disposed parallel to the axis of the rotor but at different distances therefrom, of an independent cam plate coacting with each balanced pair of pumps to control the strokes thereof.

3. In a pump of the character described, the combination with a shaft of a plurality of pairs of reciprocating pumping units associated therewith in balanced relation and disposed at different distances therefrom, of a plurality of cam plates each coacting with a pair of pumps to control the strokes thereof, and means for varying the discharge of any pair of pumps independently of the others.
4. A pump of the character described, comprising a casing, a rotor therein provided with a plurality of cylinders arranged parallel to the axis of said rotor but at different distances therefrom, plungers adapted to reciprocate in said cylinders, and a plurality of concentrically arranged cams adapted to coact with said plungers for controlling the reciprocations thereof.
5. A pump of the character described comprising a casing, a rotor therein provided with a plurality of cylinders arranged in balanced pairs parallel to the axis of said rotor but at different distances therefrom, plungers adapted to reciprocate in said cylinders, a separate cam plate inclined to the axis of the rotor and coacting with the plungers in each balanced pair of cylinders for controlling the strokes thereof, and means for independently varying the inclination of any cam plate.
6. In a pump of the character described, the combination with a rotor provided with a plurality of sets of reciprocating pumping units disposed in balanced relation at different distances from the axis of said rotor, of means providing a separate supply and discharge passage for each set of units, whereby a plurality of different liquids may be simultaneously pumped, and means for varying the discharge of each set of units.
7. In a pump of the character described, the combination with a rotor provided with a plurality of sets of reciprocating pumping units disposed in balanced relation at different distances from the axis of said rotor, of means providing a separate supply and discharge passage for each set of units, whereby a plurality of different liquids may be simultaneously pumped, and means for independently varying the discharge of each set of units.
8. A pump of the character described, comprising a casing, a rotor therein provided with a plurality of cylinders arranged parallel to the axis of said rotor but at different distances therefrom, plungers adapted to reciprocate in said cylinders, a plurality of cam plates normally inclined to the axis of said rotor and adapted to coact with said plungers to effect a reciprocation thereof, and means for varying the inclination of said cam plates independently of each other.

ARTHUR SHELDON WELDY.
